Primary Examiner — David G Muller*Assistant Examiner* — Jamaal Rasheed(74) *Attorney, Agent, or Firm* — RatnerPrestia(57) **CLAIM**

The ornamental design of a rimless toilet pan, as shown and described.

DESCRIPTION

FIG. 1 is a perspective view of a rimless toilet pan showing our new design;

FIG. 2 is a detailed view of FIG. 1;

FIG. 3 is a front elevation view thereof;

FIG. 4 is a left side view thereof, the right side being a mirror image thereof;

FIG. 5 is a top plan view thereof;

FIG. 6 is a cross-sectional view thereof taken through the front and rear sides; and,

FIG. 7 is a cross-sectional view thereof taken through the right and left sides.

The broken lines depict portions of the rimless toilet pan that form no part of the claimed design.

1 Claim, 7 Drawing Sheets
